UNITED STATES PATENT OFFICE.

HARRY T. COLDWELL, OF NEWBURGH, NEW YORK.

SPEED-CONTROLLING AND REVERSING APPARATUS FOR MOTOR-VEHICLES.

No. 902,560.

Specification of Letters Patent.

Patented Nov. 3, 1908.

Application filed February 12, 1908. Serial No. 415,544.

To all whom it may concern:

Be it known that I, HARRY T. COLDWELL, citizen of the United States, residing at Newburgh, in the county of Orange and State of New York, have invented certain new and useful Improvements in Speed-Controlling and Reversing Apparatus for Motor-Vehicles; and I do hereby declare the following to be a full, clear, and exact description of the invention, such as will enable others skilled in the art to which it appertains to make and use the same.

My invention consists in the novel features hereinafter described, reference being had to the accompanying drawings which illustrate the best form in which I have contemplated embodying it, and said invention is fully disclosed in the following description and claims.

The object of my present invention is to provide a very simple and efficient controlling apparatus for motor vehicles and the like, capable of use with the more ordinary form of change speed gearing now in use, and which is provided with means for preventing a change of speed or direction without first releasing the ordinary engine clutch, and also with means for locking the control lever in position laterally to throw in any selected gearing, and with means for further locking the lever longitudinally in the operative or inoperative position with respect to the selected gearing.

In the accompanying drawings I have shown my invention in connection with a "passing through" sliding gear change speed and reverse mechanism in ordinary use, but it is not limited in use to this particular form of gearing as variations may be made therein. For example in the form of gearing here shown, a single push rod controls the gears for three speeds ahead, and reverse, but my invention is equally applicable to gear mechanisms providing less or more speed changes, and also to those in which the reversing of the driven shaft or shaft section is effected by a separate rod or device as hereinafter explained.

Referring to the accompanying drawings. Figure 1 represents a sectional view of my control apparatus in its simplest form, adapted to be applied to a form of sliding gear change speed mechanism in which the gear changes for speeds ahead and reverse are accomplished by a single instrumentality. Fig. 2 is an enlarged plan view of the guiding

plate for the control lever, shown in Fig. 1. Fig. 3 is a detail sectional view of a form of change speed mechanism with which my invention can be advantageously employed, and in which all changes for speeds ahead and reverse are effected by the movement of a single instrumentality. Fig. 4 is a sectional view on line 4—4 of Fig. 1. Fig. 5 is an enlarged plan view of the locking plate detached. Fig. 6 is a plan view of a modified form of guiding plate for the controlling lever. Fig. 7 is a plan view of the locking plate used in connection therewith. Fig. 8 is a plan view of another modified form of guiding plate. Fig. 8^a is a detail sectional view of one of the pivoted latches. Fig. 9 is a plan view of the locking plate used in connection therewith. Fig. 10 is a detail view of a slight modification showing the lower end of the lever, and a separate shifting rod for the reverse gear. Fig. 11 is a detail of a modification of my invention. Fig. 12 is a detail plan view of the locking plate for preventing the progressive movement of the shifting lever to throw in a higher speed, without releasing the clutch.

In Fig. 3 I have shown a type of change speed gearing in which A represents the gear casing, B the driving shaft, and B' the driven shaft. Shaft B' is connected by universal joint C (or otherwise) with the driving mechanism of the vehicle. E represents the engine or motor shaft and D is the usual clutch for connecting the engine shaft with the driving shaft B. The driving shaft B is provided with pinions 1, 2, 3 and 4 rigidly secured thereto and the pinion 1 meshes with an idle pinion 5 mounted on a separate stud. On the driven shaft B' which is preferably squared is mounted a sliding sleeve B², rotatable with said shaft member and carrying the gears 6, 7 and 8. F represents a sliding bar or rod mounted in the gear case A and carrying a yoke f which engages the sleeve B² for sliding the latter on shaft B'. The rod F is preferably provided with an arm or lug f' extending upwardly therefrom and preferably having a transversely disposed head f² round in cross section, secured to its upper end. G represents the controlling lever which is mounted pivotally in a suitable standard or casing G', so that it can be swung both laterally and longitudinally. I prefer to pivot the lever between its ends in a block g', by means of a pin g, the said block having gudgeons g², g³ engaging apertures in the casing G', thus mounting the

lever practically on a universal joint. The lower end of lever G is provided with a yoke or bifurcated portion g^x which fits over the head f^2 of the lug f' on rod F, so as to engage said head in all positions to which the lever may be moved laterally. The upper end of the lever G extends through a guiding slot in a guiding plate H on top of the standard G, said plate being shown in detail in Fig. 2. The slot in the plate H extends in a series of longitudinally disposed portions connected by transversely disposed portions, so that the lever G cannot be moved from one longitudinal portion to another without moving it laterally.

In the form shown in Fig. 2, there are four longitudinal portions h , h' , h^2 , h^3 , of which h and h^2 are in line with each other and h' and h^3 are in alignment. When the lever is at the rear end of the portion h' of the slot, as shown in dotted lines Fig. 2, it will be in neutral position. To throw in the first or slowest speed the lever is pushed forward to the end of the portion h' , to throw in second speed, the lever is moved laterally, into line with the portion h^2 and then pushed forward to the end of said portion h^2 ; to throw in third speed, the lever is moved laterally into portion h^3 and thrown forward. The effect of the first of these movements in setting the gears for the first speed forward is to slide the rod F, yoke f , and sleeve B^2 rearward and to bring the gear 6 into mesh with pinion 2; the further movement of the lever in setting the gears for second speed moves the sleeve B^2 further so as to bring gear 7 into mesh with pinion 3, and the high speed is effected when the lever is moved to its extreme position in slot section h^3 , by a further movement of the sleeve B^2 , to bring gear 8 into mesh with pinion 4.

In order to reverse the vehicle, supposing the lever G to be in its neutral position, as shown in Fig. 1 and in dotted lines Fig. 2, the lever is thrown to the right into slot section h and then rearwardly to the end of the slot, thus moving rod F in the opposite direction to that above described and bringing gear 6 into mesh with the idler 5, which is preferably made with a broader face than the gear 6 or pinion 1, as shown to facilitate this operation. I also provide means for locking the lever G in position at each end of each of the slot sections h , h' , h^2 , h^3 . In this instance I have shown plate H provided with detents h^4 , h^4 at each end of each of said slot sections, adapted to be engaged by one or the other of the pawls g^5 , on a collar g^4 sliding on said lever, and operatively connected by a link g^5 with a pawl lever g^6 , arranged adjacent to the handle g' . This construction provides for locking the lever both "in" and "out" of operative position, with respect to each of the gear changes. I also provide means for locking the lever against

movement laterally, so as to prevent any change in the gearing while the clutch D is in operative position, thus necessitating the disconnection of the clutch before a change in gearing can be effected and practically preventing the possibility of stripping the gears. To this end I provide adjacent to the lower end of the casing G a laterally sliding locking plate L, shown in detail in Fig. 3. This plate is mounted in guides l so as to slide transversely and is provided with a longitudinally disposed slot l' through which lever G can move in a longitudinal direction. When the lever is moved laterally as in passing from one slot section h , h' , etc., to another the plate L must be moved with the lever. The locking plate L is provided with a plurality of locking apertures l^2 , l^3 corresponding to the number of rows of slot sections (two of such apertures being shown in Fig. 3), which are adapted to be engaged by a spring locking bolt M, mounted in the casing and provided with the spring m ; a connection m' extends from this bolt to the lever P which operates the clutch D (by means of mechanism not herein shown), the parts being so constructed that the plate L remains in locked position until the lever P is moved forward as indicated by the arrow Fig. 1 to release the clutch, when the bolt M is withdrawn and the plate L released, thus permitting a lateral movement of lever G only when and after the clutch is thrown out of operative position.

In Fig. 6 I have shown a slightly modified form of guiding plate in which the longitudinal slot sections are so arranged that no two are in line with each other, but they are in four separate lines extending progressively from one side of the plate to the other and connected by transverse slot portions as shown. The lever G is indicated in the neutral position. With this form of plate the locking plate must be correspondingly modified by providing it with four locking holes l^2 , l^3 , l^4 , l^5 , as shown in Fig. 7, otherwise the entire construction will be exactly as previously described, and will operate in the same way.

In Fig. 8 I have shown another slightly modified form of the guiding plate, in which slot sections h and h' , for the reverse and first speed positions are arranged in line with each other, the other slot sections h^2 and h^3 being progressively in separate lines from each other and from slot sections h and h' as shown. In this case I conveniently provide a pair of pivoted flaps or latches h^5 , h^6 mounted on the plate H and adapted to lie across the aligned slots h and h' so as to separate the same and prevent the operator from coming out of first speed directly into reverse or vice versa. These latches or flaps are connected in such a way that only one can lie across the slots at a

time, the other being held vertical. In this instance I provide the hinge portion of each flap with a stud h^7 (see Fig. 8^a) engaging an aperture in one end of a lever h^8 pivoted centrally to the under side of the plate H which is slotted to permit the studs h^7 to pass through the same and engage the lever h^8 . Hence when one of these flaps is raised the lever h^8 will be shifted so as to throw the other flap into horizontal position. In case the plate shown in Fig. 8 is used, the locking plate must be modified to correspond by providing it with three locking apertures l^2 , l^3 , l^4 as shown in Fig. 9, otherwise the construction and operation will be exactly as previously described.

In some cases the change speed and reversing mechanism may be so constructed that separate instrumentalities may be required for the forward speeds, and the reverse. In Fig. 10 I have shown a slight modification of my controlling device, to meet this condition. In this figure F' represents the rod for moving the gears to effect the changes of speed forward and F^2 represents a separate rod suitably connected with the mechanism to effect the reverse drive. The rod F' is provided with an arm f^3 having the transverse head f^4 similar to that previously described and rod F^2 has a similar arm f^5 having a head f^6 in line with the head f^4 . Obviously the lateral movement of the lower end of the lever here lettered G' from its neutral, to the right will cause it to release the main head f^4 and engage the head f^6 , when the reversing mechanism can be thrown into and out of operation. This form of mechanism as shown in Fig. 10 can be used with a guiding plate, such as is shown in Fig. 6 for example, or similar to that shown in Fig. 1 as may be preferred.

In Figs. 11 and 12 I have shown a modification of my invention for the purpose of locking the lever so that after pulling the lever in a direction to disengage the gears for a certain speed, it will be impossible to return to that speed without first releasing the clutch. In Fig. 11 a view is shown similar to Fig. 1, in which G' represents the shifting lever and F' the shifting rod connected with the sliding gear or gears and L' is the locking plate, all as previously described. In this instance I have shown the bolt M' for engaging the locking plate, carried on the end of one arm of a bell crank lever M^2 the other arm of which is perforated to receive a draw rod connected with the clutch lever P' . The operation of the plate L' is identically the same as that of the plate L previously described.

R represents a laterally movable locking plate, which I term the latch plate, to distinguish it from locking plate L' . This latch plate R is preferably pivoted at one end, and

is provided with a series of teeth r' , r^2 , r^3 , r^4 each having a straight face and an inclined face, as shown in Fig. 12. In this figure the dotted lines indicate the path of the lower end of the lever, in passing from neutral position in which it is there shown, into reverse and into the various speed changing positions to high speed, the lever being guided in such movements by the plate H shown in detail in Fig. 2. The latch plate R is held in operative position by spring r , and is connected, as by rod r^5 , with the clutch P' , so as to be moved laterally when the clutch lever is pressed forward in the direction of the arrow to release the clutch.

When the lever G is in neutral position the straight face of the tooth or shoulder r' lies directly in rear of the lower end of said lever, so that the lever cannot be moved to throw in the first speed, without first throwing the clutch out, thereby moving the latch plate laterally and disengaging the shoulder r' from the lever. After swinging the lever G' laterally in line with the second speed notch (Fig. 2) the shoulder r^2 will prevent the second speed gearing being thrown in except while the clutch is out, and in like manner shoulder r^3 prevents the passing from second to third or high speed except when the clutch is out. When the lever is in neutral position (Figs. 2 and 12) and is swung laterally in line with the reverse slot, the reverse gearing cannot be thrown in, unless the clutch is out, as the shoulder r^4 prevents the movement of the lever G' to effect such change. The inclined faces of the shoulders or teeth r' , r^2 , r^3 , r^4 permit the operator to pull the lever G out of reverse, to neutral, from first speed to neutral and from a higher speed to a lower, without throwing out the clutch, if it is desired to do this quickly but will effectually prevent the throwing in of reverse, or first speed, or any higher speed without first disengaging the clutch. This latch plate may be used in connection with other forms of gearing than that herein shown, as for example selective gearing, by suitable modification and it may be used with or without the locking plate L or L' .

The controlling mechanism herein shown is adapted for use with any form of change speed and reversing mechanism having any desired number of speeds forward or reverse.

While I have shown a particular form of change speed and reverse mechanism herein for the better understanding of my invention such change speed and reverse mechanism forms no part of my invention and the invention is not limited to use in connection therewith.

What I claim and desire to secure by Letters Patent is:—

1. In a controlling device for motor vehicles, the combination with a single shifting

device, of a single operating lever, pivotally mounted so as to be capable of lateral and back and forth movements, a guiding plate engaging one end of the lever and provided 5 with longitudinally disposed slotted portions, in different transverse planes, and connected by transversely disposed slotted portions, the lower end of the lever engaging said shifting device, the engaged portions 10 of said lever and shifting device, permitting the lateral movements of the lever from one slot section to any other slot section without disengagement of said parts, substantially as described.

15 2. In a controlling device for motor vehicles, the combination with a single shifting device, of a single operating lever, pivotally mounted so as to be capable of lateral and back and forth movements, a guiding plate 20 engaging one end of the lever and provided with longitudinally disposed slotted portions, in different transverse planes, and connected by transversely disposed slotted portions, the lower end of the lever engaging 25 said shifting device, the engaged portions of said lever and shifting device permitting the lateral movements of the lever from one slot section to any other slot section without disengagement of said parts, a locking de- 30 vice for positively locking the lever in line with any one of the longitudinally disposed slot sections, and a device independent of the movements of said lever, for releasing the locking device, substantially as described.

35 3. In a controlling device for motor vehicles, the combination with a single shifting device for setting the gears thereof for forward speeds, of a single operating lever pivotally mounted so as to be capable of a swing- 40 ing movement laterally and also backward and forward, a guiding plate having longitudinally disposed slotted portions in different transverse planes, and connected by transversely disposed slotted portions, for engag- 45 ing the said lever, one end of said lever en- gaging said shifting device, and being move- able laterally with respect thereto, without disengaging the same, means for locking said lever against lateral movement from one of 50 said longitudinal slot sections to another, and operative connections between said locking means and the main clutch lever, for releasing said locking means only when the clutch is released, substantially as described.

55 4. In a controlling device for motor vehicles, the combination with a single shifting device for setting the gears thereof for forward speeds, of a single operating lever pivotally mounted so as to be capable of a 60 swinging movement laterally and also backward and forward, a guiding plate having longitudinally disposed slotted portions in different transverse planes, and connected by transversely disposed slotted portions, for 65 engaging the said lever, one end of said lever

engaging said shifting device, and being movable laterally with respect thereto, without disengaging the same, a transversely movable locking plate, having a longitudinally disposed slot engaging said lever, locking means for locking said plate in position against lateral movement, and operative connections between said locking means and the main clutch lever for releasing said plate and lever only when the clutch is released, 70 substantially as described. 75

5. In a controlling device for motor vehicles, the combination with a gear shifting device, of a single hand operated lever, pivotally mounted so as to be capable of swinging 80 laterally and also backward and forward, the lower end of said lever being constructed to engage said shifting device and capable of moving laterally with respect thereto without disengaging the same and a guiding plate 85 engaging the said lever above its pivotal support, and having longitudinal slot portions arranged in different planes transversely of the plate and connected by transverse slot portions, means for locking said lever with 90 respect to said plate against movement longitudinally thereof, and separate locking devices for holding said lever against lateral movement, substantially as described.

6. In a controlling device for motor ve- 95 hicles, the combination with a gear shifting device, of a single hand operated lever, pivotally mounted so as to be capable of swinging laterally and also backward and forward, the lower end of said lever being constructed to 100 engage said shifting device and capable of moving laterally with respect thereto without disengaging the same and a guiding plate engaging the said lever above its pivotal support, and having longitudinal slot portions 105 arranged in different planes transversely of the plate and connected by transverse slot portions, locking detents on said plate adjacent to the extremities of said longitudinal slot portions, a movable pawl carried by said lever for engaging said detents, a laterally movable locking plate having a longitudinally disposed slot engaging said lever, and a locking device engaging said locking plate and holding it and said lever against lateral movement, substantially as described. 110 115

7. In a controlling device for motor vehicles, the combination with a gear shifting device, of a single hand operated lever, pivotally mounted so as to be capable of swinging 120 laterally and also backward and forward, the lower end of said lever being constructed to engage said shifting device and capable of moving laterally with respect thereto without disengaging the same and a guiding plate 125 engaging the said lever above its pivotal support, and having longitudinal slot portions arranged in different planes transversely of the plate and connected by transverse slot portions, locking detents on said plate adj- 130

cent to the extremities of said longitudinal slot portions, a movable pawl carried by said lever for engaging said detents, a laterally movable locking plate having a longitudinally disposed slot engaging said lever, a locking device engaging said locking plate and holding it and said lever against lateral movement, and operative connections between said locking device and the clutch lever for releasing the locking plate only when the clutch is released, substantially as described.

8. In a controlling device for motor vehicles, the combination with a gear shifting device of a single hand operated lever, pivotally mounted so as to be capable of swinging laterally and also backward and forward, the lower end of said lever having a portion of less width than the adjacent portion of the shifting device which engages the same, and being capable of lateral movement with respect thereto without disengaging the shifting device, a guiding plate engaging the upper end of said lever provided with a plurality of longitudinal slot portions located in different planes transversely of said plate and connected by transverse slot portions, a laterally sliding plate having a longitudinally disposed slot engaging the lever and provided with a plurality of locking apertures corresponding to the number of different planes in which the longitudinal slot sections of the guiding plate are arranged, and a locking device for engaging one or other of said locking apertures to lock the said locking plate and the lever against lateral movement without interfering with the movement of said lever in a backward or forward direction, substantially as described.

9. In a controlling device for motor vehicles, the combination with shifting mechanism for setting the gears thereof for forward speeds and reverse, of a hand lever for operating said shifting mechanism, pivotally mounted so as to be capable of swinging laterally and also backward and forward, a guiding plate having longitudinally and transversely disposed slotted portions, for guiding said lever, and a latch plate provided with projections, opposing the movement of said lever into reverse or any forward speed position, and means for moving said latch plate laterally to withdraw said projections from the path of said lever, substantially as described.

10. In a controlling device for motor vehicles, the combination with shifting mechanism for setting the gears thereof for forward speeds and reverse, of a hand lever for operating said shifting mechanism, pivotally mounted so as to be capable of swinging laterally and also backward and forward, a guiding plate having longitudinally and transversely disposed slotted portions, for guiding said lever, and a latch plate provided with projections, opposing the move-

ment of said lever into reverse or any forward speed position, and a connection between said latch plate and the clutch lever, for withdrawing said projections from the path of said lever, when the clutch is thrown out, substantially as described.

11. In a controlling device for motor vehicles, the combination with shifting mechanism for setting the gears thereof for forward speeds and reverse, of a hand lever for operating said shifting mechanism, pivotally mounted so as to be capable of swinging laterally and also backward and forward, a guiding plate having longitudinally and transversely disposed slotted portions, for guiding said lever, and a latch plate provided with projections opposing the movement of said lever into reverse or any forward speed position, said projections having beveled portions to permit the lever to move freely past said projections in one direction, and a connection between said latch plate and the clutch lever for withdrawing said projections from the path of said lever when the clutch is thrown out, substantially as described.

12. In a controlling device for motor vehicles, the combination with gear shifting mechanism, of a hand lever for operating said shifting mechanism, pivotally mounted so as to be capable of swinging laterally and also backward and forward, a guiding plate for said lever provided with longitudinally and transversely disposed slotted portions, a locking plate engaging said lever, means for locking said plate to prevent the lateral movement of said lever, a latch plate provided with locking projections opposing the movement of said lever into reverse or any forward speed position, and means for moving said latch plate laterally to withdraw said projections from the path of said lever, substantially as described.

13. In a controlling device for motor vehicles, the combination with gear shifting mechanism, of a hand lever for operating said shifting mechanism, pivotally mounted so as to be capable of swinging laterally and also backward and forward, a guiding plate for said lever provided with longitudinally and transversely disposed slotted portions, a locking plate engaging said lever, means for locking said plate to prevent the lateral movement of said lever, a latch plate provided with locking projections opposing the movement of said lever into reverse or any forward speed position, and a connection between said latch plate and the clutch lever for moving said plate laterally and withdrawing said projections from the path of the lever, when the clutch is thrown out, substantially as described.

14. In a controlling device for motor vehicles, the combination with gear shifting mechanism, of a hand lever for operating

said shifting mechanism, pivotally mounted so as to be capable of swinging laterally and also backward and forward, a guiding plate for said lever, provided with longitudinally and transversely disposed slotted portions, a locking plate engaging said lever, means for locking said plate to prevent the lateral movement of said lever, a latch plate provided with locking projections opposing the movement of said lever into reverse or any forward speed position, a connection between said locking mechanism and the clutch

lever for releasing said locking plate when the clutch lever is thrown out, and a connection between said latch plate and the clutch lever, for withdrawing said projections from the path of the lever when the clutch lever is thrown out, substantially as described.

In testimony whereof I affix my signature, in the presence of two witnesses.

HARRY T. COLDWELL.
